CIGARETTE PACKAGE AND MATCH
HOLDER

James Edmund Heraty, La Crosse, Wisc.

Application June 20, 1938, Serial No. 214,640

6 Claims. (Cl. 211—87)

This invention relates to improvements in cigarette package and match holders.

It is the primary object of the invention to provide a novel and simple device sufficiently inexpensive to be commercially practicable as a means for mounting a cigarette package and match book in conveniently accessible form on the windshield of an automobile or upon any other convenient support.

More particularly stated, it is my purpose to provide a vacuum cup with a bracket preferably constituted from a single piece of material, preferably wire, so bent and organized as to provide for the support of the open cigarette package and at the same time to provide conveniently spaced means readily engageable and disengageable with an open match book.

Other objects will appear in more detail from the following disclosure.

In the drawing:

Figure 1 is a view of the device as it appears in perspective when in use.

Figure 2 is a similar view in perspective of the device without the cigarette carton or match book.

Figure 3 is a view of the device in rear elevation.

Figure 4 is a view of the device in side elevation.

Like parts are identified by the same reference characters throughout the several views. While stampings or other materials may be used in the assembly of this device, the invention will be exemplified by description of a preferred embodiment in which the frame is made of wire.

The vacuum cup 5 made according to conventional practice of rubber or like material, is provided at its center with a specially shaped fitting 6, preferably of metal, which serves as a mounting for the cigarette and match holder frame.

A single piece of wire has its central portion 7 formed to constitute a rectangular frame closed at 8 by twisting the end strands of the wire together. As such strands are twisted they are engaged over the spool-shaped fitting 6 and the twisting is continued at 9, thus providing between the twisted portions 8 and 9 of the wire an eye 10 in which the spool-shaped fitting 6 is engaged.

Below the intertwined combined strand 9 of the wire the two terminal strands 11 and 12 extend downwardly and divergently and thence forwardly at 13 and 14 respectively beneath the projected area of the rectangular frame 7 for the support of the cigarette carton 15 engaged in such frame.

At 16 and 17 the respective strands extend upwardly along the front face of the carton and at 18 and 19 they are turned inwardly in alignment with each other to be received into the fold 20 of a match book.

The match book cover 21 has been passed through the rectangular wire frame 7 and thence folded inside of the match comb 22. The spacing between the frame 7 and the inwardly turned prongs 18 and 19 constituting the terminals of 10 the wire is such that with the frame 7 engaged in the bight 25 of the match book cover the prongs 18 and 19 will just fit into the bight 26 at the lower end of the match book and behind the striking surface 21, thus holding the match book flush and secure against the face of the cigarette carton 15.

In effect, the terminal portions 11, 12, 13, 14, 18, 19, 16 and 17 of the wire constitute a saddle in which the carton is supported with its upper 20 end constrained against displacement in any horizontal direction by the frame 7.

I claim:

1. A device of the character described, comprising the combination with a central support 25 having a connecting member, of a wire having its intermediate portion looped to constitute a generally rectangular frame spaced above said support, said wire having strands twisted together to close said frame and extending thence downwardly and embracing said connecting member, the terminal portions of said wire being twisted together to extend below said member and thence being divergent and extended outwardly beneath said frame and upwardly at the front of said 30 frame and therebelow, whereby to provide a saddle co-acting with said frame to receive and carry a carton.

2. A device of the character described, comprising the combination with a central support 40 having a connecting member, of a wire having its intermediate portion looped to constitute a generally rectangular frame spaced above said support, said wire having strands twisted together to close said frame and extending thence downwardly and embracing said connecting member, the terminal portions of said wire being twisted together to extend below said member and thence being divergent and extended outwardly beneath said frame and upwardly at the front of said 45 frame and therebelow, whereby to provide a saddle co-acting with said frame to receive and carry a carton, said saddle and wire terminals having portions spaced at an appropriate distance to be engageable in the spaced bights of 50 55

the match book for holding the book in front of the carton.

3. In a device of the character described, the combination with a support, of a carton carrier comprising an upper frame and a lower saddle and means connecting said frame and saddle, said frame and saddle being adapted to receive a carton and being provided with relatively yieldable match book engaging prongs spaced below said frame in a position to be engaged in the lower bight of a match book having said frame engaged within the top bight of its cover.

4. In a device of the character described, the combination with a frame positioned for engagement with a cigarette carton near the top thereof, of saddle means in operative connection with the frame and adapted for engagement with the lower portions of a carton held by said frame, of yieldable terminal prongs carried by said saddle means in normal and substantial alignment with each other, of a spacing below said frame such as to be adapted for detachable engagement in the lower bight of a match book when the upper bight of the cover of the match book is engaged about said frame.

5. In a skeletonized holder for a cigarette carton and a match book, the combination with a central support and a vacuum cup mounting therefor, of a substantially closed top rectangular frame connected at its rear to said support and

adapted to receive a cigarette carton and having a substantially horizontal front member over which the cover of a match book is adapted to be folded, substantially horizontal means spaced below said member in a position for engagement with the match carrying portion of a match book having its cover folded over said member, and saddle means connected with said last mentioned means at the front of a carton positioned in said frame and extending therebeneath for the support and positioning thereof.

6. In a holder for a cigarette package and a match book, the combination with an upright support and a vacuum cup mounting secured to said support intermediate its top and bottom, of skeletonized upper and lower means projecting forwardly from said support in positions to receive and carry a cigarette carton, said upper means comprising a substantially closed rectangular frame having a substantially horizontal front member over which the fold of a match book cover is adapted to be engaged, said lower means comprising a part projecting beneath said frame to carry a carton positioned thereon, and another part extending substantially horizontally in front of a front portion of a carton so carried and at a spacing from said member to engage the lower portion of a match book having its cover fold engaged with said member.

JAMES EDMUND HERATY. 30
